UNITED STATES PATENT OFFICE.

PAUL WERNER SEEWER, OF GENEVA, SWITZERLAND, ASSIGNOR TO THE ENGLISH
ELECTRIC COMPANY LIMITED, OF LONDON, ENGLAND.

MEANS FOR REGULATING HYDRAULIC TURBINES.

1,333,509.

Specification of Letters Patent.

Patented Mar. 9, 1920.

Application filed January 19, 1920. Serial No. 352,563.

To all whom it may concern:

Be it known that I, PAUL WERNER SEEWER, a citizen of the Swiss Confederation, residing at Geneva, Switzerland, have invented certain new and useful Improvements in Means for Regulating Hydraulic Turbines, of which the following is a specification.

This invention is for improvements in or 10 relating to the regulation of hydraulic turbines and provides improved apparatus of the same general character as is illustrated in my United States Patent No. 1282470.

The said patent describes means whereby, 15 in a free jet hydraulic turbine, the jet may be caused to diverge into conical form when so required, for the purpose of dissipating its force and avoiding the impartation of energy to the turbine wheel, without cutting off the flow of water. This spreading 20 out of the jet may be caused to take place very rapidly by the governor mechanism of the turbine and subsequently the water may be cut off by suitable means such as a 25 needle valve at so slow a rate that no injurious pressure effects are produced in the water supply system.

By the present invention, in hydraulic free jet turbines there is combined with the 30 nozzle and means to cause the jet to diverge, a shield interposed between the nozzle and the turbine wheel to catch the spray of a divergent jet of water and direct it away from the wheel, but provided with an aperture to permit the passage of a closed jet.

As the degree of the dispersion of the jet is related to the size of the jet opening in the nozzle a certain distance must be observed between the nozzle and the shield 40 so that it may catch and divert substantially the whole of the water issuing from the jet when this is dispersed in the form of a cone. This distance is in general smaller than that necessitated by the means commonly 45 employed for intercepting and diverting closed, that is undispersed jets. The distance between the nozzle and the shield can be further reduced by making the aperture in the shield variable with the size of the 50 jet and as small as is practicable for the passage of the jet.

According to this invention when a needle-valve or the like is provided controlling the nozzle the shield may have means

such as sliding plates to vary the size of the 55 aperture of a jet, such means being interconnected with the operating means for the needle-valve, so that as the jet is reduced in size the aperture in the shield through which it passes is reduced also. 60

The embodiment of the invention illustrated in the accompanying drawings will now be described in detail.

In the drawings—

Figure 1 illustrates one construction by 65 a vertical sectional view through the nozzle and governor mechanism, the latter being only diagrammatically indicated;

Fig. 2 illustrates in side elevation a second construction with a variable aperture 70 for the shield;

Figs. 3 and 4 are details showing the method of operation of the guide vanes for dispersing the jet, and

Fig. 5 is a detail section of the shield 75 shown in Fig. 2.

Referring to Fig. 1 the nozzle A is formed in the end of a curved water inlet pipe casting A¹ provided with a cylindrical guide A² for an axially disposed needle 80 valve B. The needle valve B has a long hollow tubular stem B¹ working in the guides A² and extending through the casting A¹ into an operating cylinder C. A piston B² secured to the stem B¹ works in 85 this cylinder and is operated by oil pressure supplied through the pipes D¹, D². Oil is distributed to these pipes by a piston valve D connected to a control lever N¹ of a governor N. Oil is admitted to the distribution valve chamber D⁴ by a port D³ and when the valve D is lifted by the governor owing to a rise in speed of the turbine, the oil passes to the pipe D¹ and thence to the 90 back end of the cylinder C and operates the needle valve B to close the nozzle A. This operation is caused to take place as slowly as may be desired by a regulating valve D⁵ in the pipe D¹, which restricts the rate of flow of the oil. Should the speed of the 100 turbine fall the valve D descends, the pipe D² and by it the front end of the cylinder C is connected with the oil supply while the back end is opened to the oil outlet D⁶. The needle valve is consequently retracted. 105

In order to make the movements of the piston B² correspond exactly with the position of the governor N it is linked to the

control lever N^1 by means of the bell crank lever N^2 and rod N^3 and thus when the piston valve D has been opened to a certain extent the piston B^2 by a corresponding degree of movement operates to return it to closed position.

Within the nozzle there are arranged 10 guide vanes E , E^1 upon radial axes arranged around the needle valve guide A^2 . Trunnions E^2 are provided for the guide vanes in the outer nozzle and other trunnions E^3 in the guide casting A^2 . The guide vanes lie normally in a plane passing through the axis of the nozzle that is parallel to the normal 15 axial flow of the water. They can however be inclined to their normal plane when desired, to impart a whirling motion to the water and thus cause the jet to spread out. To this end the trunnions E^3 are extended 20 inwardly through slots B^3 in the hollow stem of the needle valve and the spindles of the guide vanes carry short levers E^4 . These levers E^4 are operated by a control rod F which slides within the needle valve stem 25 and is provided, adjacent to the levers, with inclined slots F^1 . Blocks E^5 carried on the ends of the levers slide in the slots and thus when the control rod F is caused to slide backward away from the nozzle the guide 30 vanes are deflected.

The control rod F extends rearwardly into an operating cylinder C^1 and is provided with a piston F^2 working therein. A spring C^2 serves to press the piston rearwardly, 35 while oil is supplied under pressure through a pipe G to force the piston F^2 and with it the control rod F normally forward against the spring and hold the guide vanes E in their straight, that is uninclined position.

40 The oil supply to the pipe G is controlled by a second piston valve H which is pressed down into its normal or bottom position by a spring H^1 . The piston valve H is hollowed out to form a dash-pot or cataract provided with a piston H^2 , piston rod H^3 extending outside the valve chamber, and regulating screw H^4 . The piston rod H^3 is jointed to the control lever N^1 of the governor N .

50 The screw H^4 extends to the bottom of the perforation in the rod H^3 and controls the lateral ports opening into the space above the piston H^2 ; but this arrangement is shown in my prior Patent No. 1,282,470, 55 hereinbefore referred to.

On the front of the nozzle A there is supported a deflecting shield K in the form of a hollow casting, the front of which forms an inclined baffle K^1 lying across the path of the jet of water and provided with an opening K^2 slightly larger than the maximum size of the jet to permit the passage of the same. A large opening K^3 is provided in the under side of the casting K for the outflow 60 of water when the jet is dispersed into the

form of a spray. This water therefore flows away directly into the discharge tunnel of the turbine without touching the wheel.

In operation upon a sudden decrease of 70 load on the turbine the governor rises rapidly, draws up the piston valve H against the spring H^1 by means of cataract mechanism comprising the piston rod and piston H^3 , H^2 . Oil pressure is therefore released from behind the piston F^2 and the bar F 75 moves over immediately under the influence of the spring C^2 and deflects the guide vanes E and disperses the jet of water into a spray thus preventing any rapid rise of speed on the part of the turbine before the water is 80 cut off. The piston valve D is raised at the same time as piston valve H so that the needle valve B also moves over but more slowly owing to the retarding effect of the regulating valve D^5 , and cuts off the water. 85 While this is taking place the oil in the cataract within the piston valve H has time to leak through the adjusting valve H^4 and the spring H^1 therefore depresses the valve H slowly once more into its lowermost position. 90 The guide vanes are therefore returned to the straight or normal position and the jet, now reduced in quantity, becomes solid once more. Should the load decrease only slowly the cataract within the piston valve 95 H permits the governor N to rise without moving the valve H and thus the guide vanes are not operated, although the operation of the needle valve is unaffected. Also if the load should increase causing the governor to fall the guide vanes are not operated. Should however the oil pressure fail which might cause a dangerous rise in speed of the turbine the spring C^2 will operate the guide vanes to disperse the jet of 100 water and stop the machine. If for any other reason a dangerous rise in speed occurs, the valve H will be lifted positively by the piston H^2 on this reaching the limit of its travel within the dashpot and thus the 105 guide vanes will be operated as before described.

It will be seen that the cylinder C , piston B^2 valve D and the associated parts constitute a fluid-pressure relay for operating the 115 needle valve B . The cylinder C^1 , piston F^2 and valve H constitute a second fluid-pressure relay for operating the guide vanes E . The bell-crank lever N^2 and rod N^3 constitute a differential link-work of known type 120 for correlating the movements of the needle valve with those of the governor.

Referring to Fig. 2 the general construction of the nozzle and governor mechanism is similar to that in Fig. 1 but the deflecting 125 shield K is provided with means to vary the size of the aperture K^2 . To this end the baffle plate K^1 is hollowed out to form guides for two sliding plates L , L^1 . These plates can slide up and down in a direction parallel 130

to the baffle plate K^1 and are provided with lugs L^2 which pass through slots in the side of the deflector K . The lugs L^2 engage with slots M^1, M^2 in a rocking plate M , pivoted on the side of the deflector K . The rocking plate M is connected by a rod M^3 to a lug N^4 formed on the upper end of the hereinbefore described lever N^2 . The direction and disposition of the slots M^1, M^2 in rocking plate M is such that, as the needle valve B moves forward to close the nozzle A and in so doing rocks the lever N^2 , the plates L, L^1 are caused to slide nearer together. The lips L^3, L^4 of these two plates are formed more or less to inclose the jet and it will be seen that as the jet is reduced in size, they move closer together, so that they are always as close to the jet as is practicable without touching it. Thus, upon the guide vanes operating, to disperse the jet, very little of the water will find its way through the aperture K^2 on to the bucket.

What I claim as my invention and desire to secure by Letters Patent is:

1. In hydraulic free-jet turbines the combination of a turbine wheel, a water-nozzle for directing a jet of water thereon, a needle valve for regulating the normal flow of water, means independent of the needle valve for regulating the nozzle which act by causing the jet to diverge, and a shield interposed between the turbine wheel and the nozzle to catch the water of a divergent jet and direct it away from the wheel, but provided with an aperture to permit the passage of a closed jet.

2. In hydraulic free-jet turbines the combination of a turbine wheel, a water-nozzle for directing a jet of water thereon, regulating means for the nozzle comprising a needle-valve and means to cause the jet to diverge, a shield interposed between the turbine wheel and the nozzle to catch the water

of a divergent jet and direct it away from the wheel, but provided with an aperture to 45 permit the passage of a closed jet and means to vary the size of the said aperture operatively connected with the said needle valve.

3. In hydraulic free-jet turbines the combination of a turbine wheel, a water-nozzle 50 for directing a jet of water thereon, regulating means for the nozzle comprising a needle-valve operated by a fluid-pressure relay and means independent of the needle valve for causing the jet to diverge operated 55 by a second fluid-pressure relay, a governor for controlling both the said fluid-pressure relays, a differential link-work for correlating the movements of the needle-valve with those of the governor, and a shield interposed between the turbine wheel and the nozzle to catch the water of a divergent jet and divert it away from the wheel, but provided with an aperture to permit the passage of a closed jet.

4. In hydraulic free-jet turbines the combination of a turbine wheel, a water-nozzle for directing a jet of water thereon, regulating means for the nozzle comprising a needle-valve operated by a fluid-pressure relay and 70 means to cause the jet to diverge operated by a second fluid-pressure relay, a governor for controlling both the said fluid-pressure relays, a differential link-work for correlating the movements of the needle-valve with 75 those of the governor, a shield interposed between the turbine wheel and the nozzle to catch the water of a divergent jet and direct it away from the wheel, but provided with an aperture to permit the passage of a 80 closed jet and means to vary the size of the said aperture operatively connected with the said needle-valve.

In testimony whereof I affix my signature.

PAUL WERNER SEEWER.
